UNITED STATES PATENT OFFICE

LLOYD W. DYER, OF SWISSVALE, PENNSYLVANIA, ASSIGNOR TO WESTINGHOUSE ELECTRIC & MANUFACTURING COMPANY, A CORPORATION OF PENNSYLVANIA

CIRCUIT INTERRUPTER

Application filed April 4, 1930. Serial No. 441,520.

My invention relates to circuit interrupters and particularly to arc-extinguishing devices therefor that are immersed in a fluid.

It has been demonstrated by experiment 5 that the most important factors in the interruption of alternating-current arcs are; first, the rate of rise of recovery voltage immediately following a current zero in the cycle wave and, second, the rate of deionization of 10 the gases between the arcing contact members after the current zero point.

The rate of rise of recovery voltage can be somewhat controlled by employing resistors or condensers in conjunction with the circuit 15 interrupters, while the re-combination of ions in the arc space depends entirely upon the design and construction of the circuit-interrupting device itself.

My invention relates to deionizing devices 20 for circuit interrupters of the oil-immersed type and has for its object the retention of a portion of the liquid thereof adjacent to the arc path where it will be decomposed by the arc to liberate a deionizing gas which will 25 pass turbulently into and out of the arc stream.

Another object of my invention is to provide a circuit interrupter of the above-described type having a device that shall direct 30 gases radially into the arc stream from all points of the periphery thereof at intervals along the arc length, which gases may be vented out of the arc stream between the various said intervals.

35 A further object of my invention is to provide an arc-extinguishing device of the above-described type that is immersed in a liquid, and having a plurality of pockets disposed at intervals along the arc length that shall retain a portion of the liquid adjacent to the arc core when an arc is established between the contact members.

A still further object of my invention is to provide a device of the above-described 45 type with a plurality of cooling surfaces that shall divide the vented gases to further cool and deionize them.

A further object of my invention is to retain a substance in close proximity to the arc 50 stream, that shall provide relatively cool sur-

faces and nuclei, in the presence of an arc, upon which recombination of ions in the arc stream can occur.

For a more complete understanding of the nature and objects of my invention, reference should be had to the following description, taken in conjunction with the accompanying drawing wherein:

Figure 1 is a sectional view, in elevation, of a circuit interrupter embodying my invention,

Fig. 2 is an enlarged vertical sectional view, of a fragment of the arc-extinguishing device shown in Fig. 1,

Fig. 3 is a sectional view of a modified form of the arc-extinguishing device,

Fig. 4 is a transverse sectional view of the arc-extinguishing device shown in Fig. 3, taken along the line IV—IV thereof,

Fig. 5 is a vertical sectional view of a unit of an arc-extinguishing device similar to that shown in Fig. 3, but disclosing another embodiment of my invention,

Fig. 6 is a vertical sectional view of a portion of a structure similar to that shown in Fig. 2, but disclosing additional features of my invention,

Fig. 7 is a plan view of the structure shown in Fig. 6, and

Figs. 8 and 9 are vertical sectional views of an arc in my deionizing structure and disclosing the path of movement of the deionizing gases in the arc stream.

My invention comprises, in general, a casting 1 having a cover 2 that supports conductor bushings 3 and 4, in a manner that is well known in the art. The bushings 3 and 4 support the contact members 5 and 6, respectively, which are conductively joined by the bridging member 7 and the rods 8 and 9 which are carried on the ends of the last said member.

The bridging member 7 is supported on a lift rod 10 that extends through the cover 2 and is connected to operating mechanism (not shown). This mechanism is actuated to move the rods 8 and 9 longitudinally to connect or to disconnect them from the contact members 5 and 6, respectively, to complete or interrupt an electric circuit. Deionizing

structures 11 and 12 are supported on the terminal members 5 and 6, respectively, and are immersed in an arc-quenching liquid 13 that is contained within the casing 1. This liquid is preferably an oil that freely evolves a gas of low molecular weight when in contact with an arc, although it is to be understood that any liquid having satisfactory dielectric properties and that readily evolves gases in the presence of an arc and which possesses the desired deionizing qualities, may be substituted for the oil.

In the copending application of J. Slepian, Serial No. 411,271, filed December 3, 1929, and assigned to the assignee of the present invention, a deionizing device is disclosed which is similar to the deionizing device of my invention, but comprises a series of spaced oil-soaked plates having apertures in which the arc is drawn and held in fixed relation to the oil retained in the plates. In devices of these types, the oil is rapidly decomposed by the arc, and the gases that are evolved pass turbulently through the arc stream and the ionized space remaining after the arc is extinguished. The cooled gas particles form centers in the ionized space upon which the ions rapidly recombine to form un-ionized layers that increase in thickness at such a rate that the rise of recovery voltage after the arc is extinguished is never sufficient to cause the re-initiation of the arc.

My invention relates to devices for supplying oil to the arc stream that are constructed of materials that are only slightly affected by the arc and which, therefore, substantially retain their original dimensions.

In my present arrangement, illustrated in Fig. 1, the deionizing structures 11 and 12 comprise two or more insulating plates 14 that are spaced apart a predetermined distance by the insulating spacers 15 as shown in Fig. 2. Rods 16 extend through the spacers 15 and the plates 14 to form a unit structure 45 that is suspended from the terminal members 5 and 6, respectively. A hole 17 is provided in the center of each of the plates 14, these holes being aligned in the deionizing structure in order that the contact rods 8 and 9 may pass therethrough when moved to circuit-open or to circuit-closed position.

When an arc is drawn in a quenching liquid, a gas bubble forms about the arc stream and prevents the greater portion of the arc core from contacting with the liquid. The only portion of the arc that continually engages the liquid is that portion that impinges on the movable contact member and is drawn into the liquid as the contact member is being moved. The plates 14 are employed to increase the number of contacting points of the arc core with the liquid. The film of liquid retained on the periphery of the hole 17 remains to be decomposed by the arc after the bubble, formed about the arc core, has

forced the liquid beyond the confines of the arc stream.

It will be readily apparent that, if the diameter of the hole 17 is too large, the liquid film thereon will be at such distance from the arc core that the arc will have very little contact therewith and only a very small quantity, if any, of the deionizing gas will be generated. Numerous tests on currents up to 3000 amperes, disclosed that the holes should be less than $\frac{7}{8}$ of an inch in diameter. Holes of greater diameter produced erratic results and substantiated the belief that the film of liquid on the surface of the holes was too far from the arc stream to be rapidly decomposed by the arc.

The small holes limit the expansion of the arc and should, therefore, have an area that is equal to, or less than, the cross-sectional area of the arc core. When the arc is so confined the arc voltage increases with the increase of current, as the arc is unable to expand at the point of confinement, the current density also increases. The concentration of the current increases the rate of decomposition of the liquid which is fed radially into the arc core, at each plate around the entire periphery of the arc.

In order to prevent any increase in the size of the hole, in the presence of the concentrated arc current, it was necessary to employ a material in constructing the plate that would not be affected or would be only slightly affected by the arc. A molded asbestos compound produced satisfactory results, but plates made from fibre proved to be the most reliable in operation. The latter material is only slightly eroded by the arc, which erosion proved beneficial in preventing any metallic deposit from forming on the walls of the holes 17. The fibre material proved further beneficial in supplying to the arc stream additional un-ionized gas when the material was decomposed, by the arc. This gas effected the same deionization of the arc path as that produced by the gas of the decomposed liquid, the combination of which materially increased the rate of recombination of the ions in the arc stream.

The deionizing device shown in Figs. 3 and 4 comprises a plurality of units 18 that are composed of two or more plates of insulating material referred to heretofore. The units are separated from each other by insulating spacers 15 that are mounted on rods 16 to form a unit structure. Each of the units 18 is provided with a hole 17, through the center thereof, that is less than $\frac{7}{8}$ of an inch in diameter. The conducting rods 8 and 9 extend through the aligned holes 17 to complete a circuit with the terminals 5 and 6, respectively, and to draw arcs when the contact rods are separated therefrom when moved downwardly to open-circuit position.

The surface of the sides of the holes in the

composite plate units 18 is much greater than the surface of the holes in the single plates 14 and, consequently, larger volumes of the un-ionized gas will be liberated at each of 5 the confining portions of the units, because of the greater amount of oil clinging to the surfaces of the holes. As the rate of deionization (of the arc) is increased with an increase in the amount of un-ionized gas that 10 is continually being fed into the arc stream, the units 18 have a distinct advantage over the thin plates 14.

The unit 18 shown in Fig. 5 is provided with a central plate 20 that has a hole 21 in 15 the center thereof, having a greater diameter than the holes 17 in outer plates 22 and 23 of the unit. The hole 21 of the plate 20 forms a pocket in the unit 18, in which some of the quenching liquid 13 is trapped and 20 retained to be available for feeding into the arc stream when an arc is established through a plurality of units containing the pocket 21. Where the term "pocket" is used in the 25 claims, it means a recess having a size which is large compared to the size of the pores in the material of the plates.

As pointed out above, the hot ionized gases are forced out of the arc stream into the space 18 between the units 14 by the fresh 30 gas that is continually supplied to the arc stream. In order to more effectively cool and deionize these gases, I provide a plurality of vertical plates 24 disposed radially in the space 19 about the holes 17, as shown 35 in Figures 6 and 7. When the gas is forced through the space 18, it will be divided into a plurality of sections by the plates 24, which will cool the gases and cause them to recombine on the surfaces of the plates. The 40 plates 24 are further useful in resisting the flow of oil away from the arc stream, some of which will be retained adjacent to the arc path to be decomposed by the arc, while portions of the remainder will aid in the cooling 45 of the escaping gases.

The above-noted motion of the gas into and out of the arc stream is illustrated in Fig. 8 of the drawing, wherein curved lines 25 designate the path of travel of the various 50 particles of the gas evolved from the decomposition of the oil 13. It will be seen, from the direction of the lines and the arrows, that the gas not only passes into and out of the arc stream at intervals throughout the arc 55 length but that this passage of the gas takes place radially along the entire periphery of the arc. That is to say, the gas is supplied to the arc core radially from every point around its entire circumference. This flow 60 of gas through the arc stream begins to take place as soon as the arc is initially drawn, since the liquid is not closely confined and is free to move as the gas is formed by the decomposition of the liquid held along the 65 arc core by the edges of the openings in the

plates. The venting passages between the plates are open at all times into the liquid in the outer tank so that the gases formed by the arc can begin to flow and produce turbulence in the arc stream as soon the circuit is initially broken, thus causing the arc to be very quickly extinguished.

Taking advantage of the discovery that a deionizing gas supplied radially to the arc core at various points throughout its length 70 causes the ions of the arc space to be rapidly combined, I have invented the deionizing structure shown in Fig. 9. In this construction, the plurality of units 18, that are spaced along the arc path, are provided with an annular channel 26 that is connected to a plurality of tubes 27, which are spaced radially about the channel 26. The tubes 27 are connected to a source of supply of a deionizing 75 material that may be a powder, gas, or liquid to produce the rapid recombination of the ions in the arc space referred to hereinbefore. Suitable means, well known in the art, is employed to connect and disconnect the source of supply to the tubes 27 in relation to the 80 movement of the rods 8 and 9. The movement of the gas into the arc stream from all sides thereof further prevents the highly mobile arc from moving away from the gas which passes directly into the arc stream and 85 out of it, as disclosed by the lines and arrows of Fig. 9.

It will thus be seen that I have provided a circuit interrupter that establishes an arc 90 in a quenching fluid and a device adjacent to the arc path that retains a portion of said fluid in the vicinity of the arc by which it is decomposed to liberate deionizing gases for effecting the rapid recombination of the ions in the arc path after arc extinguishment. 95 The gas is supplied to the arc stream radially at a plurality of intervals along the arc length and is vented from the arc path between the intervals.

It will also be recognized that the distribution of gas sources along the arc is applicable where the arc is drawn in air or other gaseous media as well as in the quenching liquid specifically described herein. In fact, any device that turbulently injects a 100 deionizing medium into the arc path along its entire length, or at intervals thereof, in the presence of the arc or after the arc is extinguished, falls within the scope of my invention.

While I have described several embodiments of my invention, it is to be understood by those skilled in the art that many changes, additions, omissions and substitutions may be made therein without departing from the 105 spirit and scope of my invention, as set forth in the appended claims.

I claim as my invention:

1. In combination with circuit-interrupter contact members, of unit members each com- 110

prising a plurality of contiguous insulating plates having alined holes, the holes in some of the plates of each unit having larger dimensions than the other plates of that unit 5 for forming pockets and a substance which evolves gas when acted upon by an arc retained in said pockets.

2. In combination with circuit-interrupter contact members, of unit members each comprising more than two contiguous insulating plates having alined holes, the holes in the plates at the center of each unit having larger dimensions than the other plates of that unit for forming pockets, and a quenching 13 liquid surrounding said unit members, a portion of which is retained by said pockets after 15 said contact members are separated.

3. The combination with a liquid-immersed circuit interrupter for alternating-current circuits, of separable contact members, a plurality of insulating members spaced apart and associated with said contact members, pockets in said insulating members for retaining a portion of said liquid therein and means between said insulating members for dividing the space therebetween into a plurality of passages.

4. The combination with a liquid-immersed circuit interrupter for alternating-current circuits, of separable contact members including a thin rod, a plurality of insulating members having holes through which said rod extends and is moved to establish an arc, the said holes being not substantially greater in width than said rod, and the said insulating members having pockets formed in the periphery of said holes for retaining a portion of said liquid therein in the presence of an established arc.

40 5. In a circuit interrupter, an arc extinguishing device including means of insulating material having an opening therethrough, means for causing an arc in said opening, a plurality of pockets positioned along said opening, said pockets being closed on all sides except the side leading to said opening, and a material which evolves gas when acted upon by the arc retained in said pockets in the presence of the arc.

50 6. In a circuit interrupter, an arc extinguishing device including a stack of laminations of insulating material, openings in said laminations forming a passage through the stack, means for causing an arc in said passage, the openings in some of said laminations having a larger dimension than the corresponding dimension of the openings in other of said laminations, said laminations having the openings with a larger dimension being positioned centrally between and contiguous to said laminations having the openings with the smaller dimension, and a substance which gives off a large volume of gas when acted upon by the arc cooperating 60 with said laminations.

7. In a circuit interrupter, a pair of contacts one of which is movable and between which the circuit through said interrupter is initially broken, an arc extinguishing structure including means of insulating material having an opening therethrough in which the arc caused by the initial break of the circuit plays, said means of insulating material having portions at the edge of said opening extending substantially to the path of movement of said movable contact member, an outer casing for the circuit interrupter enclosing said arc extinguishing structure, said outer casing having a cross-section several times greater than the cross-section of said arc extinguishing structure, means along said opening for the arc which gives off a large volume of gas when acted upon by the arc, and ventilating means extending from said opening for the arc caused by the initial break of the circuit directly to the space enclosed by said outer casing.

8. In a circuit interrupter, a pair of contacts one of which is movable and between which the circuit through said interrupter is initially broken, an arc extinguishing structure including a stack of plates of insulating material, said stack having an opening therethrough in which the arc caused by the initial break of the circuit plays, said opening having portions of a width not substantially greater than the width of said movable contact member, an outer casing for the circuit interrupter enclosing said arc extinguishing structure, said outer casing having a cross-section several times greater than the cross-section of said arc extinguishing structure, means along said opening for the arc which gives off a large volume of gas when acted upon by the arc, and ventilating means extending from the portion of said opening at which the arc is initially formed directly to the space enclosed by said outer casing.

9. In a circuit interrupter, a pair of contacts one of which is movable and between which the circuit through said interrupter is initially broken, an arc extinguishing structure including means of insulating material having an opening therethrough in which the arc caused by the initial break of the circuit plays, said opening having substantially the same width as said movable contact member, an outer casing for the circuit interrupter enclosing said arc extinguishing structure, said outer casing having a cross-section several times greater than the cross-section of said arc extinguishing structure, and a body of liquid which gives off gas when acted upon by the arc in said outer casing, a plurality of pockets formed in the wall of said opening in which the arc plays, said pockets being closed on all sides except the side leading to said opening.

10. In a circuit interrupter, a pair of con-

tact members, one of which is movable for causing an arc, an arc extinguishing structure including a plurality of plates of insulating material having an opening therethrough in which the arc plays, said opening having portions of a width not substantially greater than the width of said movable contact member, an outer casing for the circuit interrupter, a body of liquid in said outer casing surrounding said arc extinguishing structure, said liquid adjacent the arc extinguishing structure being free to move immediately upon the drawing of the arc and venting means extending laterally from the path where the arc plays to said liquid in the outer casing outside of the arc extinguishing structure.

5 which the arc plays, said opening having portions of a width not substantially greater than the width of said movable contact member, an outer casing for the circuit interrupter, a body of liquid in said outer casing 70 surrounding said arc extinguishing structure, said liquid adjacent the arc extinguishing structure being free to move immediately upon the drawing of the arc and venting means extending laterally from the path where the arc plays to said liquid in the outer casing outside of the arc extinguishing structure.

10 which the arc plays, said opening having portions of a width not substantially greater than the width of said movable contact member, an outer casing for the circuit interrupter, a body of liquid in said outer casing 75 surrounding said arc extinguishing structure, said liquid adjacent the arc extinguishing structure being free to move immediately upon the drawing of the arc and venting means extending laterally from the path where the arc plays to said liquid in the outer casing outside of the arc extinguishing structure.

15 which the arc plays, said opening having portions of a width not substantially greater than the width of said movable contact member, an outer casing for the circuit interrupter, a body of liquid in said outer casing 80 surrounding said arc extinguishing structure, said liquid adjacent the arc extinguishing structure being free to move immediately upon the drawing of the arc and venting means extending laterally from the path where the arc plays to said liquid in the outer casing outside of the arc extinguishing structure.

11. In a circuit interrupter, a pair of contact members, one of which is movable to initially break the circuit by causing an arc, an arc extinguishing structure including means of insulating material positioned adjacent the point where said contacts first separate, said means of insulating material 85 having an opening therein through which said moving contact draws the arc, said opening having portions at its periphery extending substantially to the path of said movable contact member, an outer casing for the circuit interrupter, a body of liquid in said outer casing surrounding said arc extinguishing structure, and venting means extending through the arc extinguishing structure from the path where the arc plays to the liquid in the outer casing, said venting means permitting flow of fluid at any time after the circuit 90 is initially broken.

12. In a circuit interrupter, a pair of contact members connected to the terminals 40 of the circuit interrupter and a bridging bar including moving contact members for completing the electrical circuit between said contact members connected to the terminals, a stack of plates of insulating material for each cooperating pair of said contact members, said stack having an opening therethrough in which the arc plays, said opening having portions of a width not substantially greater than the width of the movable contact member, a casing enclosing said stacks of plates and said bridging bar, said casing being the only enclosure for said stacks of plates, a body of liquid in said casing, and venting means extending through each of 105 said stacks of plates from the openings in which the arcs play to said body of liquid.

13. In a circuit interrupter, a pair of contacts one of which is movable and between which the circuit through said interrupter 45 is initially broken, an arc extinguishing structure including means of insulating material having an opening therethrough in which the arc caused by the initial break of the circuit plays, said means of insulating material having portions extending substan-

tially to the path of said movable contact member, an outer casing for the circuit interrupter enclosing said arc extinguishing structure, and a body of liquid which gives off gas when acted upon by the arc in said outer casing, a plurality of pockets formed in the wall of said opening in which the arc plays, said pockets being closed on all sides except the side leading to said opening, and venting means permitting flow of fluid from said opening into said body of liquid in said outer casing at any time after the circuit is broken.

In testimony whereof, I have hereunto subscribed my name this 31st day of March, 1930. 80
